Primary Examiner — David G Muller*Assistant Examiner* — Christina Gabrielle Cosden(74) *Attorney, Agent, or Firm* — Morgan, Lewis & Bockius LLP(57) **CLAIM**

The ornamental design for a helmet shroud mount adapter, as shown and described.

DESCRIPTION

FIG. 1 is a front perspective view of a helmet shroud mount adapter showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines illustrate structure or features that form no part of the claimed design.

1 Claim, 5 Drawing Sheets(56)
